UNITED STATES PATENT OFFICE.

CLEMENT E. CHASE, OF WAYNE, PENNSYLVANIA.

DESIGN FOR AN ICE PICK.

Application filed September 17, 1926. Serial No. 19,096. Term of patent 7 years.

To all whom it may concern:

Be it known that I, CLEMENT E. CHASE, a citizen of the United States, residing at 410 Oak Lane, Wayne, in the county of Delaware and State of Pennsylvania, have invented a new, original, and ornamental Design for Ice Pick, of which the following is a specification, reference being had to the accompanying drawings forming part thereof.

Figures 1 and 3 are perspective views and Figure 2 is a top plan view.

I claim—

The ornamental design for an ice pick as shown.

CLEMENT E. CHASE.
